US00D988504S

(12) **United States Design Patent** (10) **Patent No.:** **US D988,504 S**
(45) **Date of Patent:** **** Jun. 6, 2023**

(54) **HEADGEAR**

(71) Applicant: **Fisher & Paykel Healthcare Limited**,
Auckland (NZ)

(72) Inventors: **Craig Robert Prentice**, Auckland (NZ);
Bernard Tsz Lun Ip, Auckland (NZ);
Mark Aryind McLaren, Auckland (NZ);
Kyle Gregory Brown, Auckland (NZ);
Chris Onin Limpin Hipolito,
Auckland (NZ); **Mark Richard Tomlinson**, Auckland (NZ); **Melissa Catherine Bornholdt**, Auckland (NZ)

(73) Assignee: **Fisher & Paykel Healthcare Limited**,
Auckland (NZ)

(**) Term: **15 Years**

(21) Appl. No.: **29/762,147**

(22) Filed: **Dec. 15, 2020**

Related U.S. Application Data

(60) Continuation of application No. 29/720,721, filed on Jan. 15, 2020, now Pat. No. Des. 908,206, which is a continuation of application No. 29/670,353, filed on Nov. 15, 2018, now Pat. No. Des. 876,616, which is a continuation of application No. 29/595,871, filed on Mar. 2, 2017, now Pat. No. Des. 837,971, which is a (Continued)

CLAIM

The ornamental design for a headgear, as shown and described.

DESCRIPTION

FIG. 1 is a top, front, and left side perspective view of a headgear;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

Broken lines are used to illustrate portions of the headgear that form no part of the claimed design.

1 Claim, 7 Drawing Sheets

Related U.S. Application Data

division of application No. 29/540,683, filed on Sep. 25, 2015, now Pat. No. Des. 784,515.
